UNITED STATES PATENT OFFICE.

JOHN H. FRITZ, OF KANSAS CITY, MISSOURI, ASSIGNOR TO J. R. GREEN, OF JASPER COUNTY, MISSOURI.

MIXING DEVICE FOR EXPLOSIVE-ENGINES.

1,394,820.

Specification of Letters Patent. Patented Oct. 25, 1921.

Application filed July 23, 1920. Serial No. 398,353.

To all whom it may concern:

Be it known that I, JOHN H. FRITZ, a citizen of the United States, residing at Kansas City, in the county of Jackson and State 5 of Missouri, have invented a certain new and useful Improvement in Mixing Devices for Explosive-Engines, of which the following is a specification.

My invention relates to improvements in 10 mixing devices for explosive engines.

It relates particularly to novel means for mixing an explosive charge just prior to its admission to the explosion chamber.

The object of my invention is to provide 15 novel means for obtaining a thorough intermingling of the constituents of an explosive charge just as it enters the engine cylinder, thus increasing the efficiency of the charge, effecting a saving in fuel, and reducing the 20 deposition of carbon.

My invention provides further a novel fuel mixing device which is simple in construction, cheap to manufacture, durable and not liable to get out of order, and which 25 can be readily applied to engines now in use.

The novel features of my invention are hereinafter fully described and claimed.

In the accompanying drawing, which illustrates 30 the preferred embodiment of my invention,

Figure 1 is a central sectional view of my improved mixing device shown applied to an engine cylinder.

Fig. 2 is an outside end view of the mixing 35 device.

Fig. 3 is an inside end view of the same.

Fig. 4 is a view, partly in horizontal section and partly in plan, of my improved 40 mixing devices shown applied to the cylinder and intake manifold of an engine.

Figs. 5, 6 and 7 are plan views of the three screens respectively.

Figs. 8 and 9 are plan and cross sectional 45 views respectively of a modified form of my invention.

Similar reference characters designate similar parts in the different views.

Referring particularly to Figs. 1, 2 and 3, 50 1 designates a cylinder of an explosive engine, 2, the intake port thereof, and 3 a fuel conductor which leads from the carburetor, not shown, and discharges into the port 2.

My invention aims to thoroughly mix the 55 ingredients of the charge just as the charge

is to be exploded, and to effect this I insert a screen at the outside of the intake port of the cylinder. This screen, designated by 4 and shown in Fig. 6, is disposed between two relatively coarse screens 5 and 6, Figs. 50 5 and 7, the three screens being superposed one on the other and mounted in an annular recess 7 in the outer side of an annular member 8 which bears against the outer side of the cylinder 1, and which, preferably, 65 has an annular shoulder or flange 9 fitted in the port 2. The discharge end of the fuel conductor 3 bears against the outer side of the member 8, which serves as a gasket, and which may be substituted for the gasket or- 70 dinarily used at this place.

For tightly clamping the screens 4, 5 and 6 in the recess 7, I provide a perforate member 10, preferably cup shaped, and which at its inner edge bears against the outer screen 75 5 adjacent to the periphery of the latter. The member 10 may have a central longitudinal tubular extension 11 which at its inner end bears against the central portion of the outer screen 5. Extending through the tu- 80 bular portion 10 is a screw 12, which also extends through a transverse bridge portion 13 with which the gasket member 8 is provided. A nut 14 is mounted on the inner end of the screw 12 and bears against the 85 inner side of the bridge portion 13.

When a charge is drawn into the cylinder 2 from the conductor 3, the charge passes through the clamping member 10, thence through the screens 5, 4 and 6 and thence 90 into the cylinder through the member 8 and port 2. In passing through the fine screen 4, the constituents of the charge are thoroughly intermingled, just prior to their entering the cylinder, thereby rendering the 95 combustion more perfect, thus increasing the efficiency of the charge, the power of the engine and effecting a saving in fuel and the reduction in the amount of carbon deposited in the cylinder.

The coarse screens 5 and 6 serve to support or brace the fine wire screen 4 and prevents rupture of the latter from the pressure of the gas.

When the mixing devices are to be used 105 in connection with an engine having a plurality of cylinders and an intake manifold connected with said cylinders, the devices are arranged as shown in Fig. 4. In this figure, 15 designates the intake ports in the 110

body 16, of the engine, and 17 designates the usual intake manifold.

Two gasket members 8, carrying the screens 4, 5 and 6, and the clamping members 10, as shown in Fig. 1, are inserted respectively between the discharge ends of the manifold 17 and the engine body 16 and in the ports 15 respectively.

In the form of my invention shown in Figs. 8 and 9, the three screens 4, 5 and 6 are superposed one on the other, the fine screen 4 being the intermediate screen and the three screens extending across a tubular member 18, which intermediate of its ends is provided with an annular peripheral hollow flange 19 within which the edges of the three screens are mounted and held clamped together. In applying this form of my invention to an engine, the ends of the tubular member 18 are inserted respectively in the port 2 of the engine and in the fuel conductor 3, the discharge end of the latter bearing against the annular hollow flange 19, which in turn has its inner side bearing

against the engine cylinder 1. The operation of this form of my invention is the same as has been described with reference to the other form.

I do not limit my invention to the structures shown and described, as many modifications, within the scope of the appended claims, may be made without departing from the spirit of my invention.

What I claim is:—

In a mixing device for explosive engines, a ring member having a bridge portion, three screens superposed one on the other, extending across said ring member, the intermediate screen being relatively fine, and the other screens being relatively coarse, a perforated clamping member bearing against the center and edges of the screens, and a securing device connecting the clamping member and said bridge portion, substantially as set forth.

In testimony whereof I have signed my name to this specification.

JOHN H. FRITZ.
